UNITED STATES PATENT OFFICE

DAVID DAVISON, OF OAKLAND, AND WILLIAM L. CORSON, DECEASED, LATE OF ALAMEDA, CALIFORNIA, BY JOSHUA A. ROBERTS, ADMINISTRATOR, OF ALAMEDA, CALIFORNIA, ASSIGNORS TO UNION GAS ENGINE COMPANY, OF OAKLAND, CALIFORNIA, A CORPORATION OF CALIFORNIA

AUTOMATIC CONTROL FOR INTERNAL-COMBUSTION ENGINES

Application filed January 13, 1927. Serial No. 161,006.

- This invention relates to Diesel engines of the solid or mechanical injection type and particularly to automatic fuel regulation and control.
- 5 Diesel motors of the mechanical injection type are provided with a spray nozzle, a valve in the nozzle to regulate the discharge of fuel, a pump to deliver fuel to the nozzle and means for regulating the quantity of fuel delivered to the nozzle. Engines of this type are usually subjected to considerable variations in speed and load conditions when in operation and means must, accordingly, be provided to vary the quantity of fuel injected.
- 10 Varying load and speed conditions are ordinarily taken care of either by regulating the lifting period of the spray nozzle valve or by changing the quantity of fuel delivered to the spray nozzle by the fuel pump.
- 15 In actual practice, it has been discovered that a change in the quantity of fuel injected or regulation of the spray valve lift or, in other words, increasing or decreasing the spraying or injecting period is not sufficient if efficiency and good combustion is considered as another factor enters to-wit: that of pressure regulation. It has been found that the pressure on the fuel should reach maximum during a prolonged spraying period and considerably reduced during a shorter spraying period. This is due to the fact that a greater quantity of fuel requires more energy or pressure to insure atomization, while a smaller quantity of fuel requires less energy or pressure. It has also been discovered that better control and efficiency is attained when the spraying period and the quantity of fuel injected are controlled in unison. Again, it has been found that the pressure on the fuel should be changed as the spraying period and the quantity of fuel is varied and further that the spraying period, the quantity of fuel injected and the pressure maintained should be changed with variations in speed and load.
- 20 The object of the present invention is to generally improve and simplify the construction and operation of regulating devices of the character described; to provide means whereby the spraying period, the quantity of
- 25 fuel injected and the pressure maintained may be regulated in unison and further to provide means whereby the spraying period, the quantity of fuel injected and the pressure maintained may be co-ordinated with speed variations and load conditions. One form which the invention may assume is shown by way of illustration in the accompanying drawings, in which:
- 30 Figure 1 is a side elevation of the cylinder of a Diesel motor, said view showing the application of the fuel regulating mechanism,
- 35 Figure 2 is an enlarged sectional view of the resilient coupling employed in conjunction with the connecting link 43,
- 40 Figure 3 is an enlarged sectional view of the spray nozzle and a portion of the mechanism actuating the same,
- 45 Figure 4 is an enlarged sectional view of the fuel pump and a portion of the mechanism actuating the same,
- 50 Figure 5 is an enlarged sectional view of the governor.
- 55 Referring to the drawings, in detail, and particularly Figure 1, A indicates the cylinder of a Diesel engine; B the head; C the spray nozzle; D the fuel pump; E the cam shaft whereby the exhaust and inlet valves of the motor are actuated and F a governor which is driven by the cam shaft and the function of which will hereinafter be described.
- 60 The spray nozzle is best illustrated in Figure 3 of the drawings. It consists of a body portion 2 which projects through the head B of the cylinder and which terminates in a spray tip 3. Mounted interior of the body and normally forming a closure for the spray tip is a needle valve 4. This valve projects through a stuffing box 5 and its upper or projecting end is provided with a collar 6 which is engaged by a wedge-shaped member 7. Engaging the wedge-shaped member is an intermediate rocker arm 8 which, in turn, is actuated by a main rocker arm 9. This rocker arm is, in turn, actuated by a fuel cam 10 secured on the cam shaft E and the needle valve is thus intermittently raised with relation to the spray tip so as to permit injection of the fuel. The quantity of fuel injected de-

termines the power output of the cylinder and as engines of this character are subjected to varying load conditions means must be employed for regulating the opening period of the valve. The means employed in the present instance, is the wedge-shaped member 7. This member is actuated by the governor F through a rocker arm and a series of link connections, as will hereinafter be described. Sufficeth to say that a longitudinal movement is imparted to the wedge member 7 and that this determines the lifting or opening period of the valve.

In actual practice, it has been found that it is not only necessary to regulate the quantity of fuel injected, but it is also necessary to regulate the quantity of fuel delivered to the spray nozzle and further to regulate the pressure maintained on the fuel. The means employed in the present instance is a variable discharge or metering pump, previously referred to and indicated at D. This pump is best illustrated in Figure 4, and it consists of a cylinder or body portion 11 in which is formed a cylindrical chamber 12. The upper end of this cylindrical chamber is provided with a stuffing box 13 through which extends a plunger 14. This plunger is pivotally connected as at 15 (see Figure 1) with a strap 16 which, in turn, is connected with an eccentric 17 secured on the cam shaft. This eccentric imparts a reciprocal movement to the plunger and fuel in the form of oil or the like is thus intermittently admitted and discharged by the pump. The fuel is admitted through an inlet pipe 18 and discharged through a pipe 19 which connects with the upper end of the spray nozzle C, as indicated at 19. One side of the cylinder 11 is extended as shown at 20 and this extension forms a housing for an inlet valve 21 and a discharge valve 22, these valves being interposed between the respective inlet and discharge pipes 18 and 19, as illustrated.

An intermediate chamber 23 is formed between the valves and this communicates with the cylindrical chamber 12 through means of a port 24. The fuel is admitted through the inlet pipe 18 during upward movement of the pump plunger 14 as the inlet valve will be opened both by suction and mechanical operation, during reverse movement the oil admitted will be discharged partly through the inlet valve and partly through the discharge valve 22 during the return stroke of the plunger. In fact the varied discharge or metering action obtained by the pump depends upon the mechanical closing of the inlet valve, as retension of the inlet valve in open position during a portion of the return stroke of the plunger 14 permits a certain quantity of the oil admitted to be returned through the inlet valve to the suction line 18 and the remaining oil to be discharged through the valve 22 when the inlet valve is

closed. The mechanical operation of the inlet valve is obtained by the employment of a plunger rod 25. This extends through a stuffing box 26 mounted in the lower end of the housing 20 and it is connected through means of a link 27 to a rocker arm 28 which oscillates on an eccentric 29 which is secured on a controller shaft 30 hereinafter to be described. The opposite end of the rocker arm 28 is connected through means of a link 31 (see Figure 1) with the plunger 14 at the point indicated at 32. A reciprocal movement is thus imparted to the link in unison with the movement of the plunger 14 and this reciprocal movement is, in turn, transmitted to oscillate the rocker arm 28. This, in turn, imparts a reciprocal movement to the plunger 25 which aligns with the inlet valve 21 and by regulating the position of the rocker arm 28 the closing period of the inlet valve 21 may be determined and similarly the quantity of oil bypassed or returned. If it is desired to retard closing of the inlet valve during the downward or discharge stroke of the plunger 14, it is merely necessary to rotate the shaft 30 and the eccentric 29 in the direction of arrow A (see Figure 4). This rotation of the controller shaft and the eccentric raises the rocker arm 28 and the plunger 25 and it is, accordingly, possible by adjusting the raised position of these members to retard closing of the inlet valve to any extent desired.

Two means are employed for the purpose of regulating the closing of the inlet valve: first a manual means which consists of a lever 33. This lever is keyed or otherwise secured to the controller shaft 30 and its outer end swings over a segmental rack bar 34 with which it may be interlocked by means of a spring pawl 35. Hence, by swinging the lever 33 manually, any position of the shaft 30, eccentric 29 and plunger 25 may be obtained. The other means employed for controlling the closing of the inlet valve is the governor F. This governor imparts a rocking movement to an arm 36 which is secured on a shaft 37.

A crank arm 38 is secured on the end of the controller shaft 30. This crank arm is connected with the arm 36 through means of a link 39 and rocking movement of the arm 36 is thus transmitted to elevate or lower the eccentric, the rocker arm 28 and the plunger 25 and means have, accordingly, been provided whereby the closing period of the valve may be either manually or automatically regulated. The arm 36 which is actuated by the governor also serves a function of controlling the position of the wedge member 7 whereby the opening period of the fuel injecting valve or spray nozzle is controlled. This is accomplished by providing a bellcrank or the like such as indicated at 40. This is pivotally mounted as at 41 on

- top of the cylinder head. The upper end of the bellcrank is connected with the wedge member 7 through means of a link 42 and the lower end of the bellcrank is connected with the arm 36 through means of a link 43. 5 Hence, when rocking movement is transmitted to the arm 36 through means of the governor, two automatic regulations are simultaneously attained, to-wit: automatic regulation of the quantity of the fuel discharged by the pump and automatic regulation of the fuel injector or spray nozzle valve. 10 The governor employed is also an important feature of the present invention as it does not only serve the function of automatically regulating the injection or spray nozzle and the quantity of fuel delivered thereto, but it also serves the function of maintaining such automatic regulation during a wide range of engine speeds. 15 A description of the governor mechanism is, accordingly, thought necessary and reference will be made to Figure 5. 20 By referring to this drawing, it will be noted that the governor consists of a lower housing section 45 and an upper housing section 46. Extending through these housing sections is a governor shaft 47 and secured thereon in the usual manner is a cross head 25 arm 48 in the outer ends of which is pivotally mounted as at 49 bellcrank arms 50 which carry fly balls 51. These are connected in the usual manner by tension springs 52 and they, furthermore, function in the usual manner, that is, they are actuated by centrifugal force during the revolving movement of the shaft 47 and as such have a tendency to swing outwardly against the tension of the spring 52. The inner ends of the bellcranks are 30 provided with rollers 53 and these in turn, engage the collar 54 of a sleeve 55 which is mounted for reciprocal movement on the shaft, that is, outward movement of the fly balls 51 is transmitted to impart a downward movement to the sleeve 55 and this movement is, in turn, transmitted to rock the shaft 37 and the arm 36 secured thereon, this movement being transmitted through a forked-shaped rocker arm 56 secured on the inner 35 end of the shaft 37 and engaging an annular groove or collar 57 formed on the sleeve 55. The outward movement of the fly balls 56 and the downward movement of the sleeve 55 is in the present instance, resisted by a plurality of springs such as indicated at 58 and 59. The lower ends of the springs are supported on the plate 60 which is vertically 40 slideable on the governor shaft 47, while the upper ends engage a plate 61 which, in turn, supports the lower end of the sleeve 55. A thrust bearing 62 being interposed between the lower end of the sleeve and the plate 61 to reduce friction to a minimum. The plates 60 and 61 together with the springs 58 and 65 59 are secured against rotation by passing rods 63 through the springs 58 and the plates and by securing one of the rods to the governor housing. This feature is, however, of no material importance and further description thereof is thought unnecessary. 70 An important feature is, however, that of providing means whereby the tension of the springs 58 and 59 may be varied. The means employed in the present instance is a crank arm 64 which engages the lower plate 60. This crank arm is secured on the shaft 65 which is journaled in the governor housing 75 45 and extends through one side thereof. The outer end of this shaft is provided with a manually controlled lever 66 (see Figure 1) and this lever, in turn, carries a pawl 67 which engages a rack bar 68. The position of the controlling lever 66 and the rocker arm 64 may thus be determined and maintained and the tension of the springs 58 and 59 is, 80 accordingly, regulated. These springs contact with the governor spring 52 through means of the sleeve 55 and the governor bellcranks 50 and more or less resistance may thus be imposed against the centrifugal action 85 of the fly balls and practically any speed range may be maintained. For instance, if it is desired to run the engine at slow or idling speed, the controlling lever is swung to its lowermost position with relation to the rack bar 68. This movement of the controlling lever swings the rocker arm 64 to its lowest position and thereby reduces the tension of the springs 58 and 59. Resistance to 90 outward or centrifugal movement of the fly balls 56 is thus placed at a minimum and the speed of the engine will be slow as the fly balls will swing outwardly the moment a predetermined speed is exceeded. Such outward movement is transmitted to the sleeve 95 55 and through the rocker arm 56 and shaft 37 to the controlling arm 36. This, in turn, actuates the fuel pump and the spray nozzle in such a manner that the spray valve is given its shortest opening period and the pump 100 105 its smallest discharge. 110 On the other hand, if maximum or full speed is required, the controlling lever is swung to its uppermost position shown in Figure 1. Such movement places the springs 58 and 59 under maximum compression and a greater load is thus placed on the flyballs of the governor and they will be restricted to outward movement until a maximum speed is obtained. Any intermediate speed may similarly be maintained by moving the controlling lever to any intermediate position between the maximum and minimum speeds. 115 120 125 It is thus seen that the pump suction valve and spray nozzle fuel valve controls are synchronized and operated by the governor simultaneously at minimum and maximum speeds and at any intermediate speed. This feature makes possible remarkable efficient governing. This is of further importance as 130

it eliminates the bypassing of high pressure fuel. There is, however, installed, an emergency relief valve in the oil delivery pipe 19, but this functions very rarely and as it is more or less a common expedient in installations of this character, illustration thereof, has been eliminated.

It was previously stated that the quantity of fuel discharge by the pump was under both manual and automatic control. Such an arrangement is also provided in conjunction with the fuel or spray nozzle valve, that is, the opening period of the valve is both automatic and manually regulated. The automatic control, through means of the governor has already been described. The manual control is only employed when starting, as greater quantities of fuel is required. It consists of a manually controlled lever 70 pivotally mounted on top of the cylinder head as indicated at 71. This lever is connected with a bellcrank 40 through means of a link 72. The end of the link which connects with the bellcrank is slotted as shown at 73 and as such does not interfere with the normal automatic action of the governor. Another feature is required in connection with the manually control to-wit: an extensible coupling on the link or rod 43 as indicated at 74 (see Figures 1 and 2). The link or rod 42 is divided into two sections, the uppermost section being screwed or otherwise connected with a nut 75 which extends into and is secured in the upper end of the coupling 74. The lower end 35 of the rod projects through the coupling 74 and is slidably therein.

A head member is secured on the lower section of the rod and a spring 77 is interposed between said head member and the lower end 40 of the coupling. Hence, when starting the engine and requiring a greater quantity of fuel, it is only necessary to pull the controlling lever 70 downwardly in the direction of arrow B (see Figure 1). Such a 45 downward movement is transmitted through the link 72 to pull the rocker arm 40 in a forward direction thereby placing the wedge 7 in a position where the opening period of the needle valve will be increased and the 50 quantity of fuel injected proportionately increased. The moment the engine is started the controlling lever 70 is swung back to normal position and automatic regulation is then depended upon. The spring coupling 74 permits such temporary forward movement of the crank arm 40 due to the fact that the coupling can move upwardly with relation to the lower section of the rod 43. When the 55 bellcrank is returned to normal position by returning the controlling lever to normal position, the head member 76 engages the nut 75 and the rod will then function as a rigid unit.

It was previously stated that pressure regulation of the fuel was one of the important

factors of the present invention. To make this matter as clear as possible, it should be understood that maximum quantities of fuel is injected during maximum engine speed and loads and that the quantity of fuel injected during reduced loads and speeds is materially decreased. Actual experience has determined that the best results are obtained as far as efficiency and good combustion is concerned when the pressure on the fuel is increased during maximum injection of fuel and proportionately decreased during reduced injection of fuel. This is due to the fact that more energy in the form of pressure is required to atomize a greater quantity of fuel and it is also due to the fact that perfect atomization of a small quantity of fuel is not desired when running under slower speeds or idling conditions, as coarser atomization causes slower combustion during idling speeds which is a desirable feature, while more or less perfect atomization causes rapid combustion with a tendency towards pinging or knocking. It is for this reason that pressure regulation is maintained.

It is usually stated and commonly thought that liquids are incompressible. It is, however, known that water is compressible to a slight degree and it is also known that hydrocarbon oils or, in other words, fuel oil such as employed in Diesel motors is compressible to a greater degree than water. This compressibility of the oil or fuel is taken advantage of in the present instance. The pressure range on the fuel ranges from 3,500 pounds during maximum loads to approximately 1,000 pounds at minimum or idling loads and the pressure regulation is maintained by variable discharge of the metering pump. When the discharge of the pump is maintained at maximum, the greatest pressure is obtained on the oil as a greater body of oil is forced into the pressure lines or pipes and the spray nozzles which have a given or predetermined capacity. On the other hand when the discharge of the pump is maintained at a minimum, a smaller quantity of oil is discharged in the pressure line and spray nozzle and the pressure will, accordingly, drop to a minimum as a smaller quantity of oil is delivered into a space of predetermined capacity. It is, accordingly, evident that variation in pressure is obtained due to the variable discharge of the pump and the compressibility of the oil and it is further evident that the pressure will be at minimum when the discharge of the pump is the smallest and that a maximum pressure will be obtained when the discharge of the pump is the greatest.

From the foregoing description, it will be understood that a controlling mechanism has been provided which is both manual and automatic in operation and that by the automatic control obtained through means of the

governor, it is possible to simultaneously vary the spraying period, the quantity of oil injected and the pressure maintained and further that such control may be automatically maintained during all speed ranges between the maximum and minimum speed of the engine.

While certain features of the present invention are more or less specifically described, I wish it understood that various changes may be resorted to within the scope of the appended claims. Similarly that the materials and finishes of the several parts employed may be such as the manufacturer may decide or varying conditions or uses may demand.

Having thus described the invention, what I claim and desire to secure by Letters Patent is:—

1. In a mechanical injection Diesel engine, a spray nozzle, a pump adapted to deliver fuel thereto, a valve in the spray nozzle, automatic actuated means to vary the opening period of the valve and the quantity of fuel delivered by the pump in unison, a manual control connected with the valve to vary the opening periods, a manual control on the pump to vary the quantity of fuel delivered, said manual controls being operable independent of the automatic control and being also operable independently of each other.

2. In a mechanical injection Diesel engine, a variable discharge fuel pump, a spray nozzle having a valve, means to vary the opening period of the valve, a governor driven by the engine, a manual control for the governor whereby the governor may be adjusted to act at any speed range between a maximum and minimum speed, and means actuated by the governor at maximum, minimum, or any intermediate speed whereby the quantity of fuel discharged by the pump is increased as the valve opening period increases so that synchronous co-operation of the pump and valve is insured.

DAVID DAVISON.
JOSHUA A. ROBERTS,
Administrator of William L. Corson, Deceased.
